UNITED STATES PATENT OFFICE.

HENRY WELLENCHECK, OF NEW YORK, N. Y.

DESIGN FOR A CLASP FOR NECKLACES AND SIMILAR ARTICLES OF JEWELRY.

52,926.

Specification for Design.

Patented Jan. 28, 1919.

Application filed August 7, 1918. Serial No. 248,814. Term of patent 14 years.

To all whom it may concern:

Be it known that I, HENRY WELLEN-CHECK, a citizen of Russia, (who have declared my intention to become a citizen of the United States,) residing at New York city, in the county of New York and State of New York, have invented a new, original, and ornamental Design for a Clasp for Necklaces and Similar Articles of Jewelry, of which the following is a specification, reference being had to the accompanying drawing, forming part thereof.

Figure 1 is a side elevation of a clasp embodying my design, and Fig. 2 is a similar view in a plane at right angles to that in Fig. 1.

I claim:

The ornamental design for a clasp for necklaces and similar articles of jewelry as shown.

HENRY WELLENCHECK.
